BY

UNITED STATES PATENT OFFICE.

JOSEPH LOUIS CYRILLE NOËL AND JOSEPH EMILE NOËL, OF OTTAWA, ONTARIO,
CANADA.

AUTOMATICALLY-LOCKING HAND-BAG.

1,223,855.

Specification of Letters Patent. Patented Apr. 24, 1917.

Application filed October 18, 1915. Serial No. 56,562.

To all whom it may concern:

Be it known that we, JOSEPH LOUIS CYRILLE NOËL and JOSEPH EMILE NOËL, both subjects of the King of Great Britain, and residents of the city of Ottawa, Province of Ontario, Dominion of Canada, have invented certain new and useful Improvements in Automatically-Locking Hand-Bags, of which the following is the specification.

This invention relates to improvements in hand bags or purses. The hand bag at present largely used is extremely liable to swing or be otherwise opened and has been found in many cases to attract the unwelcome attention of pickpockets, and one of the objects of the present invention is to render the hand bag or purse automatically self locking and incapable of being tampered with when hung from a chain or other suspending member. Further objects are to simplify the construction and reduce the number of working parts and generally to adapt the several parts to better perform the functions required of them.

With the above objects in view the invention consists essentially of the improved construction of hand bag or purse particularly described and set forth in the following specification and accompanying drawings forming part of the same.

In the drawing,

The figure is a fragmentary elevation of a hand bag embodying the present invention.

Referring to the drawing, A represents a hand bag of any usual type provided with angle reinforcing members 10 along the upper edges, such angle members being hinged at 11 and adapted to be opened under the action of the spring 12 mounted on the hinged pin.

Mounted on the upper angle member 10 intermediate of the length thereof is a catch member B comprising a Z-shaped lever 13 pivotally mounted intermediate of its length between the jaws 14 and adapted to engage at one end with the orifices 15 and 16 which are adapted to register when the angle members 10 are in closed engagement.

The other offset end of the lever 13 terminates in a finger piece 17 and is adapted to be normally pressed upwardly by the spiral spring 18 located therebelow, the said lever

being housed in a casing 19 rigidly mounted 55 on the outer face of the upper angle member.

Equidistantly spaced on opposite sides of the catch member B are a pair of catch members C adapted to be actuated when the bag is suspended from the chain 20 or other 60 hand grip.

The members C each comprise a crank member 21 pivotally mounted on the casing 22 and adapted to be retracted by a spiral spring 23, the protruding ends of the said 65 crank members being rigidly attached to the ends of the U-shaped links 24 connected to the ends of the chain.

The arm of the crank member 21 is designed to engage the slots 25 in the angle 70 members 10 in a manner to be made clear hereafter.

In using the bag it will be clear that when it is suspended from the chain 20 the arms of the crank members 21 will engage 75 the slots 25 in the members 10 so that it is not possible to open the bag while in this position, even though the Z-shaped lever 13 has been manually actuated to disengage one end of the same from the orifices 15 80 and 16 in the members 10.

When the bag has been laid down, as for instance when in stores, it will be seen that the spiral springs 23 cause the engaging arms of the crank members 21 to be withdrawn 85 from engagement with the slots 25 so that when the lever 13 has been actuated through the medium of the finger grip 17 the purse may be opened.

In a purse of this nature it is quite impossible for pick-pockets to open the same when in use since the members C are automatically locked when the bag is suspended from the hand of the owner and it is only possible to gain access to the bag when the 95 tension on the chain 20 has been released.

As many changes could be made in the above construction and many apparently widely different embodiments of our invention within the scope of the claim, constructed without departing from the spirit or scope thereof, it is intended that all matter contained in the accompanying specification and drawings shall be interpreted as illustrative and not in a limiting sense.

What we claim as our invention is:

In a bag and in combination, superimposed reinforcing members for the bag lips

having registering slots therein, pivoted catch members movable into said slots to lock the bag lips together adapted to be automatically actuated when the bag is suspended 5 from the hand grip, and resilient means for unlocking the catch members when the tension on the hand grip has been released.

In witness whereof we have hereunto set our hands in the presence of two witnesses.

JOSEPH LOUIS CYRILLE NOËL.
JOSEPH EMILE NOËL.
